UNITED STATES PATENT OFFICE.

DE ELBERT A. REYNOLDS, OF WEEHAWKEN, NEW JERSEY, ASSIGNOR, BY MESNE ASSIGNMENTS, TO AUDIPHONE COMPANY OF AMERICA, OF NEW YORK, N. Y., A CORPORATION OF DELAWARE.

AUDIPHONE.

Application filed June 17, 1918. Serial No. 240,418.

To all whom it may concern:

Be it known that I, DE ELBERT A. REYNOLDS, a citizen of the United States of America, residing at Weehawken, county of 5 Hudson, State of New Jersey, have invented certain new and useful Improvements in Audiphones, of which the following is a specification.

My present invention has special reference 10 to telephone apparatus designed to gather and electrically transmit vibrations or sound-waves emitted some distance from the apparatus, on the principle of the audiphone, with provisions for electrical transmission, 15 and essentially embraces a sensitive transmitter with means for gathering such sound waves and conveying them to such transmitter. This has heretofore been attempted through the use of a large mouth-piece or 20 horn, the sound waves or vibrations striking the transmitter or horn in substantially a straight line and conveying to the instrument all jars and echoes attendant such sound waves.

Such a form of construction is open to 25 serious criticism in telephone practice, because of the dominant energy of the stronger or harsher vibrations, and the exclusion or smothering of the fainter sound waves. A 30 clearly defined resonance is also noticeable when the horn or mouth-piece is directly attached to the body of the transmitter, imposing on the electrical voice currents not only the vibrations of the diaphragm through 35 the variable resistance of the carbon particles, but also the jar or resonant tone of the horn. There is also the objection of a too direct action upon the diaphragm of those sound waves reaching the diaphragm 40 through the center of the horn, while those sound waves encountering the horn at an angle are impinged against the slanting sides of the horn, and are practically neutralized in force, thereby failing to transmit 45 the fainter vibrations which are requisite to give timbre to the reproduced articulations.

To overcome these and other objections, and to neutralize the attendant echo, I have discovered that a non-resonant receptacle 50 of a general bell-shape, for gathering and synchronizing the sound waves independently of electrical transmission, combined with a diaphragm-provided sensitive transmitter but so related to such receptacle

whereby all vibrations other than those directly transmitted to the center of the diaphragm are excluded from effective relation with the diaphragm. Such bell-shaped receptacle is provided with a curve extending inwardly at the center for directing the sound waves from all parts of the receptacle to the center of the diaphragm, and a shield is so positioned within the receptacle as to attain an effectual horn having substantially no irregularities therewithin to break or impede the sound waves. Preferably, I also provide means for adjusting the transmitter relative to the receptacle so that a greater or less volume of sound may reach the diaphragm, thus adapting it to all varying 70 conditions of use.

A particular structural feature of the present invention comprises a bell-shaped sound collector embodying non-vibratable material and provided with a conical projection at its central zone, a base provided with an opening, the walls of which form a sound passage with the walls of such conical projection and a microphone having its vibratable diaphragm exposed to sound waves transmitted through such sound passage. Such base is preferably mounted adjustably within the sound collector, to thereby adjust the effective direction and effective cross sectional area of such passage. Such microphone is preferably provided with a contact and means for regulating the pressure of such contact, such pressure regulating means being supported by such base.

The invention as a whole is designed to be 90 formed of individually separable parts constructed and arranged to be readily assembled, and to permit ready adjustment of the respective parts after assembly.

Further features and objects of my invention will be understood from the following description and accompanying drawings, in which—

Fig. 1 is a sectional view of my invention showing the transmitter and its relation to 100 other parts of the apparatus; and

Fig. 2 is a front elevation of Figure 1.

In the drawings forming part of my specification, 1 represents a bell-shaped receptacle of non-resonant material, preferably made of aluminum with a coating of felt, or two aluminum receptacles 1^a, 1^b, with felt 1^c between. 2 represents a bracket or support

for the receptacle, 3 is a spider having the outer ends of the spider arms secured in any suitable manner to the receptacle 1. To the inner ends of the spider arms is attached the 5 ferrule 4 and set-screw 5 for adjustably securing the rod 6.

The transmitter comprises preferably, a curved frame 7, having a central opening 7^a serving as the inlet opening of the transmitter, and further provided with means 10 for supporting the diaphragm 8 of the transmitter. The transmitter further comprises the felt ring 9, enclosing the granular carbon 10, constituting the variable 15 resistance in the transmitter circuit. The front electrode 11, or carbon button, is carried by the diaphragm 8, and is positioned at one end of the felt ring 9, whereas the other electrode 12, or carbon disc is positioned at the opposite end of the felt ring 9.

13 and 14 represent flexible rings or washers for the purpose of steadyng the periphery of the diaphragm 8 without gripping it too tightly; 15 is an adjustable plate 20 of slight resiliency, oval in form, with a slightly extended point 16 at the center engaging the carbon disc 12 and combining with means hereinafter set forth for exerting pressure upon the disc 12, and therewith on the felt ring 9 and ultimately on the diaphragm 8, whereby the diaphragm 8 is given a slightly convex form upon which the sound waves impinge.

17 is a box-shaped container of suitable 25 material, and constructed to encase the diaphragm 8, felt ring 9, carbon disc 12, granular carbon 11, and plate 15, in such a manner as to accord free workings of all the parts, and serving as a base for the adjustment screws 18, 19 and 20. Said container 17 is provided with a central recess 21, within which the rod 6 is seated. The base 17 is preferably inserted in the frame 7 by screw threading, or by set screws 22 45 or equivalent adjustable means for exerting any desired tension upon the flexible rings 13 and 14. The frame is preferably recessed at its periphery to receive the shield 23, of non-resonant material, which is attached to 50 the rod 6 by means of a set-screw 24.

Between the spider 3 and the bell-shaped receptacle 1, I prefer to insert felt washers 25, and a felt ferrule 26 between the spider 3 and the rod 6, in order to preclude the 55 transfer of any vibrations from the bell-shaped receptacle 1 to the diaphragm 8.

The front electrode 11 is preferably attached to the diaphragm 8, by means of a small bolt 27, also serving as a terminal for 60 the wire 28, leading to the binding post 29. The other terminal 30 may be attached to the plate 15, and the other lead wire 31 passed through an aperture 32 in the base 17 and the aperture 33 in the shield 23 and connected to the binding post 34.

From the above description it will be noted that all sound waves received by the bell-shaped receptacle from any direction are conveyed to the transmitter by the bell-shaped receptacle, and that the enveloping 70 bell-shaped receptacle condenses without distortion all received sound waves upon the center of the diaphragm, thereby affording substantially perfect reproduction of the voice currents by electrical transmission by 75 means of variable resistance of the granular carbon of the transmitter.

Preferably, my non-resonant receptacle is constructed to comprise the conical projecting portion 35 and the curved frame 7 80 with an inwardly flaring, circular opening 7^a, the longitudinal axis of which is in substantial alignment with the axis of the conical projection 35. Also, the curved frame 7 is preferably provided with a compression 85 chamber 36 communicating centrally with the intake opening 7^a and coacting with the diaphragm 8, to increase the sensibility of the transmitter.

While it is possible to use many forms 90 of transmitter in my audiphone, I find that a transmitter especially designed for faint vibrations is far more satisfactory; the special form of transmitter set forth above as one preferred form of a part of my invention is advantageous in that the pressure upon the diaphragm is centrally exerted by means of the adjustable flexible plate and the yieldable felt ring, thereby giving the diaphragm a rounding or oval form of an 100 audiphone, such ring constituting, at the same time, a receptacle for the granular carbon. Such pressure means acts as a flexible damper means for the diaphragm, rendering the transmitter extremely sensitive 105 to faint sound waves, and at the same time affording more adjustability to meet varied requirements than is possible with prior art devices.

I have found that where two or more 110 damper springs are employed upon a diaphragm, more or less removed from its center, that an uneven tension obtains thereby impairing transmission, which disadvantages are magnified when a finer adjustment 115 is attempted in the effort to correctly transmit the fainter sound waves, or vibrations emitted at some distance from the apparatus. This is entirely overcome by a substantially central pressure upon the diaphragm. My adjustment means enables the operator to regulate the tension or damper upon the diaphragm to meet any condition that may arise, and is constructed to be adjustable, for any desired degree of sensitivity, after the apparatus has been fully 120 assembled.

My present invention is essentially an 125 electrical audiphone, designed to collect distant sound waves or vibrations of the 130

air, and through a variable resistance, transmit the same electrically. In connection with a multiplex induction coil, such as the one described in my pending application, 5 Serial Number 203,382, entitled Induction coils, filed November 22, 1917, a number of electrical audiphones may be employed in one or several places, the vibrations or sound waves from which will be perfectly synchronized, while by the use of the invention of Egbert A. Reynolds and myself, as described in our pending application Serial Number 183,215, entitled Sound reproducing instrument, filed July 28, 1917, those 10 sound waves are amplified to any desired extent, effectually reproducing in an audible manner, and without the aid of an ear-piece or other apparatus, the music, dialogue or other articulations from the rostrum of a theatre, a pulpit or the like, to any and all parts of the edifice, or to distant points. 15 Whereas I have described my invention by reference to specific forms thereof, it will be understood that many changes and modifications may be made without departing from the principle of the invention. 20 I claim: 25

1. In an electrical device, a sound collector provided with an inner projecting portion, a transmitter disposed within said sound collector and means for adjustably mounting said transmitter relative to said

projecting portion, said mounting means comprising a member in fixed relation to said sound collector, an element secured to 35 said transmitter and adjustable means connecting said member and said element.

2. In an electrical device, a sound collector provided with an inner centrally disposed projecting portion, a transmitter disposed within said sound collector and means for adjustably positioning said transmitter, said positioning means comprising a member in fixed relation to said sound collector and provided with a recess, an element carrying said transmitter and projecting through said recess and adjustable means for holding said element in said recess. 40 45

3. In an electrical device, a sound collector provided with an inner centrally disposed conical projecting portion, a transmitter, a member comprising a plurality of arms, means for securing said arms respectively in fixed relation to said sound collector, said member being provided with a substantially central recess, an element carrying said transmitter and projecting through said recess and a set screw for securing said element in adjustable position 50 55 60 in said recess.

In testimony whereof I have signed this specification this 4th day of June 1918.

DE ELBERT A. REYNOLDS.
